UNITED STATES PATENT OFFICE.

ARTHUR E. MATTESON, OF CHICAGO, ILLINOIS.

ARTIFICIAL TOOTH-CROWN.

SPECIFICATION forming part of Letters Patent No. 297,704, dated April 29, 1884.

Application filed September 17, 1883. (No model.)

To all whom it may concern:

Be it known that I, ARTHUR E. MATTESON, of Chicago, in the county of Cook and State of Illinois, have invented a certain new and useful Improvement in Artificial Tooth-Crowns and Material Therefor, of which the following is a specification.

My invention relates to artificial tooth-crowns which are to be applied to natural roots remaining in the mouth after the natural crowns have been removed.

The object of my invention, more particularly, is to improve artificial tooth-crowns—such, for instance, as that patented to me June 15, 1883, as No. 280,052; but it will be understood, of course, that my improvements are applicable in the construction of other crowns than that described in my said patent. In my said patent I have described an artificial tooth-crown having a metal shell or body portion struck up or otherwise formed into the desired shape. The crown shown in my said patent is provided with a porcelain front. In some instances, however—as for back and side teeth—the porcelain portion of the crown may be omitted as unnecessary. In my present improvement I construct the metal or shell portion of an artificial tooth-crown of a compound plate or strip of gold and platina. The compound plate may be made by sweating, soldering, or otherwise securing a plate of fine gold to a plate of platina, the compound plate being rolled to the required thickness—say thirty to thirty-five standard plate gage; or 35 the gold may be deposited on a platina plate or strip; or the two metals may be otherwise secured together in ways known in the art of metal working and manufacture. The compound plate or strip of platina and gold may be struck up to form the crown, or the metal shell or metal portion thereof, by suitable dies—for instance, as described and claimed in an application filed by me October 12, 1883; or it may be formed into the desired shape in other 45 ways. The platina side of the compound plate should be the inner side or surface of the

hollow crown, and the gold side should be the outer or external surface, for the sake of appearance, and for other purposes well understood by those skilled in the art of dentistry. 50 By the use of the compound metal I am enabled to use a very thin plate or shell, and still retain the requisite strength, which is very desirable in setting artificial crowns. Further, by making the platina side of the plate 55 or shell the inner side thereof, the amalgam usually used in setting crowns may be employed without danger of amalgamation with the shell or plate, as would be the case were gold alone employed as the metal of the shell. The platina 60 also enables me to use pure or fine gold to solder the parts of the shell or crown together without danger of fusing the shell, the melting-point of platina being very high.

In Figure 1 of the accompanying drawings 65 I have shown an enlarged view of a metal plate from which my improved crowns are constructed, *a* being the gold plate or side, and *b* the platina side or plate thereof; and in Figs. 2 and 3 I have shown, respectively, a sectional view of a root and crown, the crown having the shell or body portion made up of my compound plate and a porcelain front, as in my aforesaid patent, and a view in elevation of a completed crown of that description. 75

The amalgam filling and retaining post or screw usually employed are designated, respectively, by *c* and *d* in Fig. 2.

Of course my improvements may be used with other forms of crowns than that particularly patented by me, as above recited. 80

I claim herein as my invention—

An artificial tooth crown or shell, or portion thereof, constructed of a compound plate of gold and platina, substantially as described. 85

In testimony whereof I have hereunto subscribed my name this 14th day of September, A. D. 1883.

ARTHUR E. MATTESON.
